[57] ABSTRACT

[57] **ABSTRACT**
A straight bar knitting machine and method of forming thereon a rib border followed by loop transfers for changing to fashioned non-rib fabric, with loop doublings in the last knitted rib course, in which two groups of loop transfer points are used for the loop doublings and embody fashioning groups of points, with pattern controlled lever, trip and ratchet means for causing the fashioning groups of points and the remainder to be relatively displaced and held in and out of mutual alignment, and loop filling-up points associated with the groups of points to fill up holes during fashioning by widening.

FIG. 15.

STRAIGHT BAR KNITTING MACHINES

This invention is for improvements in or relating to straight bar knitting machines for making selvedge knitted blanks for garments each blank having a body portion and a rib border such for example as required for ladies jumpers, pullovers, cardigans and the like having a rib waist band and rib cuffs on the sleeves. In order to provide such a garment with desired fitting properties, it is usual to produce the rib border on a greater number of beard needles than is required for the body portion, and consequently before knitting the body portion onto the rib border it is usual to reduce the number of side by side loops of the last knitted rib course to that of the first knitted course for the body fabric by a loop transferring process known as "loop doubling". In this process an appropriate number of loops in the last knitted rib course are transferred inwardly of the course to form with adjacent loops doubled loops at such substantially equally spaced locations in the course as to reduce the number of side by side loops to the number required for starting to knit the body fabric.

It has been proposed to effect such loop doubling and to fashion the body portion by loop transference using two transfer point combs in the usual narrowing head of the machine such that for the loop doubling the point combs have imparted to them a series of loop-transfer and laterally displacing re-set motions, and for fashioning, the point combs have imparted to them usual widening or narrowing motions with the point combs at outwardly displaced locations so that only a small inner fashioning group of the points of each comb co-operate with a small group of selvedge needles at each side of the blank.

As well known, in widening this normally causes the formation of holes in the fabric, and to avoid this a filling-up point is slidably operable at the inner side of each point comb to fill up such holes. In one known arrangement the filling-up points are half points operated in known manner to spread loops laterally over the holes, but this method is not always suitable. In a spear point arrangement, spear type filling-up points are operated in known manner to pick up those individual loops immediately behind the holes and to carry such loops forwardly over the holes. However to carry out the spear point arrangement requires a precision operation at a time when the points are boxing with their associated beard needles during which the points not only press the beards of the needles in the loop transfer process but they do so with such necessary force as to deflect the needles and their loops out of alignment with the remaining needles and their loops and it is at this precise stage when the spear points must be disposed in accurate registry with those loops which are to be picked up. Normally this creates no problem when only the usual narrow transfer point fingers are used for fashioning since all the points are utilized to box with associated needles on all occasions of fashioning almost any width of blank, and therefore the interrelationship between deflected needles, non-deflected needles, and their loops, is constant at all times. Contrary to this when wide groups of points are used first for loop doubling and then for fashioning, there are times during the fashioning of wide fabric, such as for body portions, when a plurality for example two thirds, of the points are beyond the ends of the needle row, under these

conditions the extent of deflection of the end groups of needles which co-operate with the remaining points is different from other occasions during the fashioning of narrower fabric, such as for narrow parts of body portions or for sleeves, when all the points co-operate with associated needles intermediate the ends of the needle row. These different extents of deflection of needles results in variation in the interrelationship between the deflected needles, the non-deflected needles and their loops, such that if the spear type filling-up points are initially set to suit say the wide fabric, a difficulty is that the setting is unsatisfactory for the narrow fabric and vice versa. Thus a problem exists to how to overcome the difficulty, and an object of the invention is to provide for loop doubling and fashioning by use of rows of transfer points in such improved manner as to avoid such difficulty.

The invention provides a method of producing selvedge knitted blanks each having a body portion and a rib border and embodying transferred loops comprising loop doublings between the body portion and the rib border and fashioning loops at the selvedges, which method includes imparting loop transfer operations to a pair of aligned rows of loop transfer points to form the loop doublings, imparting loop transfer operations to inner fashioning groups of the points to form the fashioning loops, effecting relative displacements between the inner fashioning groups of points and the remaining outer groups of points to bring the points into the alignment required for the loop doublings and out of such alignment when required for the inner fashioning groups of points to form the fashioning loops, and when the fashioning loops are for widening imparting filling-up operations to filling-up points at the inner end of the inner fashioning groups of points to fill up widening holes in satisfactory manner for all widths of the selvedge knitted blanks. The invention also provides in a straight bar knitting machine, loop transfer means comprising, a narrowing head having a pair of adjusting point bars, a pair of loop transfer point combs carried by the point bars respectively, means mounting outer and inner groups of points in the combs for relative displacements between such outer and inner groups of points into and out of mutual alignment thereof, and controlled operating means operably associated with the point combs and adapted for effecting the relative displacements of the groups of points at required times. Conveniently the machine has a greater number of frame needles than the machine needles, means for knitting a rib border on the machine needles and spaced frame needles, means for transferring the loops last knitted on the machine needles to intervening frame needles between the spaced frame needles, means for operating the point combs to effect the loop doubling in the course of loops on the frame needles under control of pattern mechanism, means under control of the pattern mechanism for displacing the outer groups of points out of alignment with the inner fashioning groups of points, means for knitting non-rib fabric onto the course of loops on the frame needles, means for operating the point combs for the inner fashioning groups of points only to fashion the non-rib fabric including, when widening, operating the filling-up points, and means under control of the pattern mechanism for displacing the outer groups of points back into alignment with the inner fashioning groups of points.

In one arrangement the outer groups of points are slidably displaceable upwardly and downwardly relative to the inner fashioning groups of points.

Conveniently the controlled operating mechanism for the outer groups of points includes trip mechanism adapted for releasably holding the outer groups of points in each position to which they are displaced. Conveniently also the controlled operating mechanism includes an operating lever having a bifurcated end for releasable engagement with the trip mechanism during raising and lowering motions of the narrowing head. The loop doubling mechanism is conveniently under control of a disc control shaft and the same control shaft has a control element for instigating displacement of the outer groups of points following the completion of the loop doubling. Said bifurcated lever is conveniently under control of said control element through the medium of reversible ratchet means. Conveniently prop means are operable for releasably holding the mechanism in its different operated conditions. Conveniently also the mechanism is in duplicate one for each point comb.

In order that the invention may be more readily understood reference will now be made to the accompanying drawings in which:

FIG. 1 is a perspective view of needles and rib fabric showing transfer of machine needle loops to frame needles as previously proposed in a straight bar knitting machine.

FIG. 2 is a diagrammatic view of a first loop doubling stage as previously proposed in the transition course, using point combs,

FIG. 3 is a similar view to FIG. 2 showing a later loop doubling stage.

FIG. 4 is a similar view to FIG. 3 showing a further loop doubling stage,

FIG. 5 is a diagrammatic view of the rib fabric with the loop doublings and having non-rib body fabric knitted onto it, and with only an inner fashioning group of points in operative position.

FIG. 6 is a diagrammatic view of the fabric showing a first widening stage,

FIG. 7 is a similar view to FIG. 6 showing a later widening stage with operation of a filling-up point,

FIG. 8 is a similar view to FIG. 7 showing a further widening stage with a widening hole filled up.

FIG. 9 is a diagrammatic front view of needles and points arranged for loop doubling.

FIG. 10 is a similar view to FIG. 9 with the points arranged for fashioning on wide fabric.

FIG. 11 is a similar view to FIG. 10 with the points arranged for fashioning on narrow fabric.

FIG. 12 is an enlarged front view of point combs.

FIG. 13 is a cross sectional view of one of the point combs.

FIG. 14 is an enlarged cross sectional view of controlled operating mechanism for parts of the point combs.

FIG. 15 is a detail view of propping means for said mechanism.

Referring to FIG. 1, vertical beard needles 1 have co-operating with them spaced horizontal latch needles MN as disclosed for example in G.B. U.S. Pat. No. 1,295,853, to which reference may be made although only the following description is necessary for a proper understanding of the present invention. Rib fabric RB is knitted on the needles MN and on spaced ones of the

needles 1. Loop spreader elements LSE are carried by the needles MN. When it is required to change from rib to non-rib fabric the needles MN are advanced to spread their loops L, and their associated loop-less needles 1 are raised through these loops so that upon retraction of the needles MN the loops become transferred to the loop-less needles 1 thus forming with the loops on the other needles 1 a non-rib course on all the needles 1. In accordance with said Application the number of side by side loops in the non-rib course is greater than the number required for starting non-rib fabric, and for this reason loop doubling is effected at spaced locations. For this purpose a pair of rows 2, 2a of loop transfer points 3, 3a FIGS. 9 to 11, are operated 15 as hereinafter more fully described for the points 3 with reference to FIGS. 2 to 4.

Referring to FIG. 2 the row 2 of points 3 are shown after having picked up one set of loops LL near the centre of the knitting section and having transferred 20 the loops LL one needle inwards to form a first loop doubling LL. This leaves a loop-less needle 1a. Next the row 2 of points 3 is re-set outwardly and is again operated to form a second loop doubling L2, FIG. 3, and this is repeated a required number of times until the innermost point 3P registers with the loop-less needle 1a. Then the row 2 of points 3 is given a two-needle inward transfer to form a further loop doubling such as L3 25 FIG. 4 which also provides the needle 1a with a loop. This sequence is continued progressively outwardly until the number of side by side loops is equal to that required for starting non-rib fabric, as disclosed in said Application.

After knitting a number of rows of non-rib fabric NR onto the rib fabric RB as shown for example in FIG. 5, points 3b of an outer group not required for fashioning are rendered ineffective and points 3c of an inner fashioning group only are operative in this example for widening.

During the widening and when the points 3c in known manner box with their associated selvedge needles 1s, FIG. 6, these needles 1s are deflected by the points 3c out of alignment with the remaining needles LR as shown. A filling-up point FP at the inner end of the points 3c, being then disposed over a loop L4 in the last one course C, is operated to penetrate the loop L4. Next, the points 3c and FP are eased forwards and the needles again become aligned with each other as in FIG. 7.

Then the points 3c and FP lift their loops upwards and transfer them one needle outwards whereupon they re-engage the next needles, FIG. 8, to which the loops are transferred by the points.

It will be seen from FIG. 8 that the filling up loop L4 extends across the hole H which was formed by the widening.

This method of filling up widening holes is known practice in itself, but it is to be noted that in the present instance the inner fashioning points 3c and the filling up point FP are operated while the remaining points 3b are maintained ineffective.

An important advantage of the arrangement is explained with reference to FIGS. 10, 11. FIG. 10 shows the inner fashioning points 3c, 3cl in position for co-operating with selvedges of wide fabric WF, and FIG. 11 shows the same inner fashioning points 3c, 3cl in position for co-operating with selvedges of narrow fabric NF. In each instance the remaining points 3b, 3bl of

outer groups are inoperative on the needles. It will be therefore appreciated that, contrary to when the point combs have been used heretofore for loop doubling and fashioning, the deflection of needles during fashioning is constant for all widths of fabric, and this ensures that filling up of widening holes is satisfactory for all widths of fabric for which point combs are employed for loop doubling.

For controlled operation of the rows of points they are in the form of loop transfer point combs 4, 5 as shown in FIG. 9, and they are mounted in the machine's usual narrowing head by the comb 4 being carried by an adjusting bar 6 and the comb 5 being carried by an adjusting bar 7, such bars being the usual point bars through which fashioning points are operated for fashioning by loop transference.

The point combs 4, 5 consist of mounting plates 4a, 5a, to which are secured the inner groups of fashioning points 3c, 3cl, and which have vertical slideway formations for slide plates 8, 9, FIGS. 10, 11, which carry the outer groups of points 3b, 3bl.

The vertical slideways are shown at 10, 11, 12, 13 in FIG. 12 and this figure also shows that the filling-up point fingers 14, 15 are also mounted on vertical slideways 16, 17 and they have upper extensions 18, 19 through which they are operated in known manner.

The slide plates 8, 9 also have upper extensions 20, 21, 22, 23 through which they are operated.

These extensions have upper end hooks 24 to 27, see also FIG. 13, which hook onto operating rods such as that shown at 28 in FIG. 14, the hooks 26, 27 being on the rod 28 and the hooks 24, 25 being on another similar rod not shown.

Referring to FIG. 14 the usual arms which carry the narrowing head in pivotal manner are represented by the arm 29 on a shaft 30. This arm 29 carries the bars 6, 7 the rods such as 28, rods such as 31, 32, 33 and a bracket 34.

On the rod 32 is a control lever 35 one arm 35a of which is connected to the rod 28 and the other arm 35b of which has an end roller 36 and laterally projecting peg 37. For releasable co-operation with the peg 37 is a trip lever 38 to one arm 38a of which is connected a spring 39 and the other arm 38b of which has two spaced recesses 38c, 38d and an end nose portion 38e. The trip lever is pivoted at 38f to the bracket 34. For co-operation with the roller 36 and nose portion 38e there is a lever 40 pivoted at 40a to a frame part 41 and one arm 40b of this lever is bifurcated to form two fingers 40c, 40d.

Normally the roller 36 is engaged between the fingers 40c, 40d, as shown, with the nose portion 38e bearing against an end face 40e of the fingers 40d such as to hold the trip lever 38 clear of the peg 37. In the position shown, the outer group of points carried by the plate 8 is in its normal down position for loop doubling, and the peg 37 is held by the roller 36 engaging between the fingers 40c, 40d, opposite the recess 38d. Consequently when the narrowing head next descends, carrying the control lever 35 and the trip lever 38 with it, the spring 39 acts to engage the recess 38d with the peg 37 to maintain the plate 8 in its down position. Upon upward return of the narrowing head the parts revert back to the positions shown, and this is repeated as many times as is necessary for the number of loop doublings required.

For changing to fashioning, the bifurcated lever 40 is operated, by means to be hereinafter described, to lower its arm 40b so as to displace the roller 36 and the trip arm 38 to raise the plate 8 to its effective position. At this stage the peg 37 is disposed opposite the recess 38c so that when the narrowing head next lowers, the peg 37 engages in the recess 38c to maintain the plate 8 in its ineffective position. Upon upward return of the narrowing head the parts revert back to the positions with the peg 37 opposite the recess 38c as many times as is necessary for fashioning and until the bifurcated lever 40 is reverse operated to return the parts to the positions for loop doubling again in the next blank.

For operating the bifurcated lever 40 its other arm 40g is connected by a link 40f to an arm 42 on a rod 43 and also on the rod 43 is a ratchet wheel 44 having a limited number of teeth 45, 46, at opposite locations. For operating the ratchet wheel 44 a pair of pawls 47, 48 are carried by arms 49, 50 on the rod 43 which are connected by links 51, 52 to a cam follower lever 53 engaging a cam 54 on the machine's cam shaft 55. In addition there is a control plate 56 having steps 56a, 56b at opposite locations for control of the pawls 47, 48. This control plate 56 is connected by a link 57 to a control lever 58 which is operated by the pattern bits of a control disc 59 on a pattern control shaft 60 which is racked on as and when required in usual manner.

There is further provided a prop mechanism, FIG. 15, in which there is connected to the control lever 58 a link 61 which through a spring 62 and pin and slot 63, 64, is connected to a pawl 65 pivoted at 65a and having releasable engagement with either of two teeth 66, 67 of an arm 68 which is carried by the rod 48.

The arrangement is such that with the bifurcated lever 40 in the position shown, i.e. with the plate 8 down, the pawl 47 was the last to operate through operation of the link 57 by the control lever 58 (see dotted position) being on a pattern bit of the control disc 59. In this position of the parts the pawl 65 would engage the upper tooth 67 to hold the racked parts operated. When the plate 8 is required to be lifted to ineffective position, the control lever 58 (see full line position) would drop off the pattern bit to displace the control plate 56 so as to render the pawl 47 inoperative and the pawl 65 operative. Thereby the ratchet wheel 44 would be racked clockwise for lowering the arm 40b of the bifurcated lever 40 to raise the plate 8 to the ineffective position as hereinbefore referred to. In this position of the parts the pawl 65 engages in the lower notch as shown in FIG. 15 for holding the racked parts operated. It will be understood from this how further operations of the racking mechanism takes place for the further operations required of the plate 8.

It is also to be noted that the controlled operating mechanism as herein described is wholly or in part duplicated for acting respectively on the two rods such as 28 for required control of the two plates 8 and 9 and their outer groups of points.

It is to be also noted that the pattern control of operations of these points starts to take place for loop doubling in timed relation to pattern control of the machine to change from rib knitting to non-rib knitting.

What we claim is:

1. A straight bar knitting machine having a greater number of frame needles than the machine needles, loop transfer means comprising a narrow head having a pair of adjusting point bars, a pair of loop transfer

points combs carried by the point bars respectively, means mounting outer and inner groups of points in the combs for relative displacements between such outer and inner groups of points into and out of mutual alignment thereof, controlled operating means operably associated with the point combs for effecting the relative displacement of the groups of points at required times, means for knitting a rib border on the machine needles and spaced frame needles, means for transferring the loops last knitted on the machine needles to intervening frame needles between the spaced frame needles, loop doubling means for operating the point combs to effect the loop doubling in the course of loops on the frame needles under control of a pattern mechanism means under control of the pattern mechanism for displacing the outer groups of points out of alignment with the inner fashioning groups of points, means for knitting non-rib fabric on to the course of loops on the frame needles, means for operating the point combs for the inner fashioning groups of points only to fashion the non-rib fabric including, when widening, operating the filling-up points, and means under control of the pattern mechanism for displacing the outer groups of points back into alignment with the inner fashioning groups of points.

2. A machine according to claim 1 wherein the outer groups of points are slidably displacable upwardly and

downwardly relative to the inner fashioning groups of points.

3. A machine according to any of claim 1 wherein the controlled operating means for the outer groups of points includes a trip mechanism adapted there releasably hold the outer groups of points in each position to which they are displaced.

4. A machine according to any of claim 3 wherein the controlled operating means includes an operating lever 10 having a bifurcated end releasably engagable with the trip mechanism during raising and lowering motions of the narrowing head.

5. A machine according to any of claim 4 wherein the loop doubling means is under control of a disc control 15 shaft and the same control shaft has a control element for instigating displacement of the outer groups of points following the completion of the loop doubling.

6. A machine according to claim 5 wherein the bifurcated lever is under the control of said control element through the medium of a reversible ratchet means.

7. A machine according to claim 6 including prop 20 means for releasably holding the controlled operating means in its different operated positions.

8. A machine according to claim 7 wherein the controlled operating means is in duplicate for each point comb.
